UNITED STATES PATENT OFFICE.

EDMUND FRANKLYN WEBBER, OF NEW YORK, N. Y.

AUTOMATIC WRAPPER SEAL AND LOCK.

SPECIFICATION forming part of Letters Patent No. 784,770, dated March 14, 1905.

Application filed March 15, 1904. Serial No. 198,322.

To all whom it may concern:

Be it known that I, EDMUND FRANKLYN WEBBER, a citizen of the United States, and a resident of New York, in the county of New York and State of New York, have invented certain new and useful Improvements in Automatic Wrapper Seals and Locks, of which the following is a specification.

My invention relates to improvements in that class of wrapper sealing and locking devices commonly known as "seals" employed in securing the contents of envelopes or wrappers of parcels, packages, &c.

It has for its special object to provide suitable means of substantial protection by devices adapted for locking and sealing without the aid of a sealing-press, and I therefore call it an "automatic" seal.

In the accompanying drawings, Figure 1 represents a top plan view of the outer or exposed seal-plate, which is in this example embossed in rings and other characters mainly for the purpose of stiffening the thin sheet metal of which it is made. Fig. 2 is a transverse section of said plate on line 2-2 of Fig. 1, also a section of part of a wrapper to be sealed and a side elevation of an outside staple employed in the sealing. Fig. 3 is a top plan view of an inside seal-plate. Fig. 4 is a transverse section of said inside seal-plate and a part of the wrapper to be sealed and a side view of another staple for application inside to clench with the outside staple. Fig. 5 is a transverse section of both seal-plates and parts 35 of the wrapper and side views of both the staples inserted, but not clenched. Fig. 6 is a section same as Fig. 5, but with both the staples clenched. Figs. 7 and 8 are side views of the outside staple represented in Fig. 2, 40 one of said views showing a slight modification of construction. Fig. 9 represents an elevation of the inside staple as seen looking in a direction at right angles to the view of said staple shown in Figs. 4 and 5. Fig. 10 is a detail in section, on a larger scale, of the two seal-plates and parts of the envelop, showing a modification of the inner seal-plate. Fig. 11 is another detail in section, also on a larger scale, of the two seal-plates and part of 50 the envelop and elevations of parts of the sta-

ples illustrating more clearly the locking features of the staples.

A represents the outside seal-plate. It is preferably a disk of thin sheet metal and has outer and inner embossed rings *a* and *b* and intermediate embossed characters *c* and *d* for stiffening purposes. Within the inner ring *b* are two slots *e*, placed oppositely to each other diametrically of the plate and in parallel relation to each other, and two other slots *f*, 60 similarly placed in a line at right angles to the line of slots *e*.

B represents the inner seal-plate of like disk form and having slots *e'* and *f'*, corresponding with slots *e* and *f* of plate A. This disk is preferably plain; but it may have its margin turned downwardly, as at *g*, Figs. 4, 5, 6, and 11, or it may be upturned, as at *h*, Fig. 10.

In Fig. 9 I represent a fastening-staple, 70 preferably of sheet metal, with prongs *h* to be inserted from the inside of the wrapper first through the slots *f* of plate B, then through the laps *i* and *j* of the wrapper, and then through the slots *f* of plate A. This 75 staple has wing-like extensions of the head *l*, bent into the hook shape shown in Figs. 4, 5, and 9, so as to occupy the positions shown in said figures. In Figs. 7 and 8 I represent another staple of like material whose prongs *m* 80 are to be inserted first through slots *e* of seal-plate A, then through the laps of the wrapper, and then through the slots *e'* of the inner seal-plate B, so that the points *n* extend into the hooks *k* between their shanks and points, 85 as best seen in Fig. 5. The hooks *k* and prongs *m* of the respective staples are then pressed down by the fingers of the operator and clenched, as shown in Figs. 6 and 11, and the prongs *h* of the inside staple are clenched down 90 over the head *o* of the outside staple, thus completing the closure of the seal in such condition that opening and reclosing cannot be effected without clearly showing distortions manifestly indicating the fact. 95

The prongs *m* of the outside seal may be nicked, as shown at *o'* and *p*, so as to cause further distortion when the closure is effected and to provide points for more effectually engaging the ragged edges of the punctured 100

webs of the wrappers when being surreptitiously detached.

What I claim as my invention is—

The combination of the outside and inside seal-plates having the two pairs of coincident slots respectively in different radial lines, inside staple having the oppositely-placed hooks of the head, the prongs of said staple adapted to be inserted through the slots of one pair, and the outside staple having prongs adapted to be inserted through the slots of the other pair and into the hooks of the inside staple,

15 said prongs and hooks adapted to be clenched on the inside seal-plate by hand-pressure and the prongs of the inside staple adapted to be similarly clenched on the head of the outside staple and on the outside seal-plate.

Signed at 329 Third avenue, in the county of New York and State of New York, this 12th day of March, A. D. 1904.

EDMUND FRANKLYN WEBBER.
